CASING FOR CAPS AND CONNECTORS

Lawrence P. Mellyn, Gloucester, R.I., assignor to
General Electric Company

Filed Mar. 17, 1969, Ser. No. 16,280

Term of patent 14 years

Int. Cl. D13—03

U.S. Cl. D26—1

FIG. 1

FIG. 2

FIG. 3

FIG. 4

FIG. 5

FIG. 6

FIG. 7

FIG. 1 is a front perspective view of a casing for caps and connectors wherein my design is embodied in a connector;

FIG. 2 is a front elevational view thereof;

FIG. 3 is a side elevational view thereof;

FIG. 4 is a top plan view thereof;

FIG. 5 is a bottom plan view thereof;

FIG. 6 is a back elevational view thereof;

FIG. 7 is a rear perspective view of a modified form of a casing as shown in FIG. 1 wherein my design is embodied in a cap and wherein the power and grounding blades are shown in phantom.

The broken lines shown on the drawing are for illustrative purpose only.

I claim:

The ornamental design for a casing for caps and connectors, as shown and described.
